Primary Examiner — Robert M Spear(74) *Attorney, Agent, or Firm* — Fay Sharpe LLP(57) **CLAIM**

The ornamental design for a tire tread, as shown and described.

DESCRIPTION

FIG. 1 is a perspective view of a tire tread of the present application;

FIG. 2 is a side view thereof;

FIG. 3 is a front view thereof; and,

FIG. 4 is an enlarged, partial front view of the full tire. The broken lines defining the inner bead and the sidewall depict subject matter that forms no part of the claimed tire tread design, and are included for the purpose of illustrating the full tire. The tread pattern is understood to repeat uniformly throughout the circumference of the tire. The other side view is the same as the illustrated side view.
